UNITED STATES PATENT OFFICE.

PIERRE BASMAISON, OF SAN FRANCISCO, CALIFORNIA.

PLANE BIT.

Application filed August 15, 1922. Serial No. 581,984.

To all whom it may concern:

Be it known that I, PIERRE BASMAISON, a citizen of the United States of America, and a resident of the city and county of San Francisco and State of California, have invented a new and useful Plane Bit, of which the following is a specification.

My invention relates to bits for wood-working tools and especially plane bits. One 10 of the objects of my invention is to provide a plane bit having a replaceable cutting edge. Another object of the invention is the provision of a plane bit of the character described in which the replaceable element when dull may be quickly discarded 15 and another one easily inserted in its place and in which the structure is one of simplicity and strength.

My invention possesses other objects and 20 features of advantage, some of which, with the foregoing, will be set forth in the following description of my invention. It is to be understood that I do not limit myself to the showing made by the said description 25 as I may adopt variant forms of my invention within the scope of the claims.

Referring to the drawings: Figs. 1 and 2 are respectively perspective views of different forms of my invention. Portions of 30 Fig. 2 are broken away to reveal the structure. Fig. 3 is a perspective view of the lower end of the cutter blade. Fig. 4 is a perspective view of the cutter. Fig. 5 is a side elevation of a modified form of my invention. Portions of the figure are broken 35 out to reduce the length thereof. Fig. 6 is a side elevation of the lower end of another modified form of my bit. Fig. 7 is a vertical sectional view thru a portion of a low angle 40 block plane showing a modified form of my invention particularly adapted for such planes. Fig. 8 is a vertical sectional view thru another form of my invention.

Referring first to Fig. 1, my invention 45 comprises a cutter blade 2 beveled at its lower end 3, preferably at an angle of about 25 degrees, and provided adjacent the end with a groove 4 extending transversely across the blade parallel to the beveled edge 50 thereof. In Figs. 1, 2 and 3 the groove is shown extending into the surface of the blade at substantially right angles to the surface thereof. This groove constitutes a 55 socket in which is seated a complementary member or flange 6 formed on the rear edge of the cutter 7, the front edge 8 of which is

sharpened and forms the cutting edge of the bit. The parts are proportioned so that the cutter may be pushed into position on the blade from the side, the flange 6 seating 60 snugly in the groove and the sharpened edge 8 of the cutter overhanging the edge of the blade sufficiently to make the cutting edge effective.

Means are provided for clamping the cutter to the blade and such means also functions at its lower edge as a chip breaker. Such means comprises a clamp plate 9. As will be observed from an inspection of the drawings the cutter blade of my plane bit is 70 quite similar to the cutter of the standard woodworkers' plane and my clamp plate is also similar to the so-called cap of the double iron of such plane, being secured to the cutter blade by means of a screw 10 threaded 75 into the clamp plate and passing thru a slot 11 in the blade in the same manner as in the case of the well known double iron. The lower portion 12 of the clamp plate is however offset somewhat and at the extreme 80 lower end is curved inwardly again to form a contact with the cutter 7 immediately back of the cutting edge, this distance being adjusted in accordance with the character of 85 the work upon which the plane is used as will be understood by all woodworkers. In order to prevent the pressure of the clamp plate raising the rear end of the cutter, additional means are provided for pressing down the rear end so that no possible chattering 90 or loosening of the cutter may occur.

A second clamp plate 13 is provided with lugs 14 at the side thereof, as shown in Fig. 1, adapted to interlock in slots 15 formed in the side of the main clamp plate. The 95 second clamp plate extends downwardly between the offset portion of the outer clamp plate and the cutter blade, overlying the inner edge of the cutter. Extending across the second clamp plate is a bead 16 adapted 100 to be engaged by the under surface of the outer clamp plate so that when the screw 10 is tightened both clamp plates are pressed resiliently against the cutter, the outer clamp plate pressing on the cutter above or beyond the supporting edge of the cutter blade, and the inner clamp plate always pressing on the cutter well within the supporting edge of the cutter blade, these positions not being materially altered by adjustment of the clamp plate to move the chip 105 breaking edge of the outer clamp plate 110

nearer or farther from the cutting edge of the cutter. Any slight inequality in the alignment of the edges of the clamp plate is compensated for by the resilience of the 5 inner clamp plate. The resilient pressure of the clamp plates on the cutter when the bit is not assembled in the plane is preferably light enough to permit the cutter to be pushed transversely out of its seat without 10 loosening the screw 10, but when the bit is assembled in the plane, the lower end is caught between the clamp of the plane and the frog, and the two clamp plates are then placed under high pressure so that the cutter 15 is securely held.

To change the cutter after it has become dulled the bit is removed from the plane and the cutter pulled out from the side. A new one may then be pushed in and secured 20 by tightening the screw, being resiliently held by the clamp plates and firmly secured by the application of the clamp of the plane. It is contemplated that the cutters will be ground and honed ready for the most exacting 25 use and sold in cartons, containing a dozen or more, at a price which will make it cheaper to replace dulled cutters with new ones than to take the time to sharpen the cutter of the standard plane, but it will be obvious that in an emergency the clamp 30 plates may be moved back and the cutter sharpened. It is also contemplated that cutters ground to different bevels adapting them for various classes of work may be used. It is but the work of an instant to substitute one cutter for another so that 35 perfect adaptability of the tool for the work in hand may be had.

To facilitate removal of the cutter, notches 40 18 are formed in the clamp plates to expose the ends of the cutter.

In Fig. 2 I have shown a modified form 45 of my device which differs from that already explained chiefly in the provision of a second screw 21 for independently securing the inner clamp plate 22, which in this instance is shown riveted at its upper edge to the main clamp plate 23. In order that the lower face of the bit may be flush adjacent its 50 lower end, a beveled head screw seating in a beveled aperture in the cutter blade 24 is used, the screw passing thru a slot 25 in the inner clamp plate and being threaded into a nut 26 resting on the inner clamp plate 55 and lying in a slot 27 formed in the main clamp plate. The slot 27 prevents the correspondingly shaped nut from turning, yet with the slot 25 permits relative longitudinal movement between the parts as made necessary 60 by the adjustment of the clamp plates on the cutter blade. A screw 29 threaded into the clamp plate 23 serves to secure the clamp plates and cutter blade together. In this form of my device, the inner clamp plate 65 is relied on to hold the cutter when the

bit is out of the plane, the outer clamp plate being sprung so that little or no pressure is exerted by it. It is obvious therefore that after removing the bit from the plane, only the screw 21 need be loosened to permit 70 removal of the cutter. The screw 29 is loosened only when adjustment of the chip breaking edge of the clamp plate 23 is desired. When the bit is assembled in the plane, the plane clamp supplies the necessary pressure upon the outer clamp plate to 75 securely hold the cutter.

Both of the clamp plates, as shown in Figs. 1 and 2, are provided with an aperture 28 adapted to engage the adjusting stud of the 80 plane mechanism.

In Fig. 5, I have shown another modified form of my device in which a single clamp plate 31 is secured to the cutter blade 32 by the customary clamp screw 33. In this case the cutter 34 is formed with two cutting edges, as shown, and provided with a bead 36 running longitudinally across the center of the cutter and adapted to engage in a complementary groove or socket formed in the 90 cutter blade. The unexposed or inner cutting edge of the cutter is engaged below the flange 37 extending transversely across the cutter blade and rigidly secured to or integral therewith. The engagement of the inner edge of the cutter under the flange 37 prevents rising of the inner edge when the pressure of the clamp plate is applied close to the overhanging edge of the cutter. 95

Fig. 6 shows a somewhat similar modification in which the cutter is provided with a flange 38 making an obtuse angle with the body of the cutter and engaging in a similarly disposed slot in the cutter blade 39. Clamp plate 41 is the same as that shown in Fig. 5. Because of the angular engagement of the cutter flange in the blade, pressure of the single clamp is sufficient to hold the cutter securely. 105

In Fig. 7, I have shown an adaptation of 110 my invention particularly suitable for block planes. In this case the beveled end of the cutter blade 42 is turned upwardly and the cutter 43 is so formed as to overlie both the flat and beveled portions of the end of the cutter blade as shown. The cutter is provided with a flange 44 adapted to seat in a correspondingly formed groove in the cutter blade and is held in position by the clamp 45 of the plane mechanism. 115

In Fig. 8, I have shown still another embodiment of my invention in which the cutter blade 51 is formed with a rabbet at its beveled end in which the cutter 52 lies. In this case the cutter is a flat strip of steel having 120 preferably two areas 53 pressed outwardly from its lower face to engage similar depressions in the rabbet, so that displacement of the cutter after assembly under the clamp plate 54 is prevented. The clamp 125 130

plate is provided with a flat engaging surface 55 adapted to lie flush upon the cutter. When the bit is placed in the plane, the clamp of the plane pressing downwardly on the clamp plate insures a rigid holding of the cutter.

It will be noted that any of the forms of my invention explained above may be used with a standard plane without alteration of the plane.

I claim:

1. A plane bit comprising a cutter blade formed with a socket adjacent the lower edge thereof, a cutter having a portion complementary to said socket, a clamp plate overlying the blade and cutter, a second clamp plate overlying the blade and cutter, and means for drawing both clamp plates and the cutter blade together, said clamp plates bearing on said cutter on each side of the end of the said cutter blade.

2. A plane bit comprising a cutter blade formed with a socket adjacent the lower edge thereof, a cutter having a portion complementary to said socket, a clamp plate overlying the blade and bearing on the cutter beyond the edge of the blade, a second clamp plate overlying the blade and bearing on the cutter within the edge of the blade, and means for drawing the clamp plates and cutter blade together.

3. A plane bit comprising a cutter blade formed with a socket adjacent the lower end thereof, a cutter having a portion complementary to said socket, an outer clamp plate apertured to receive the adjusting stud of the plane and overlying the blade and cutter, an inner clamp plate secured to the outer clamp plate and overlying the blade and cutter, and means for independently clamping each plate and the blade together to secure the cutter on the blade, said outer and inner clamp plates respectively bearing on said cutter beyond and within the end of said cutter blade.

4. A plane bit comprising a cutter blade formed with a socket adjacent the lower end thereof, a cutter having a portion complementary to said socket, an outer clamp plate apertured to receive the adjusting stud of the plate and overlying the blade and cutter, an inner clamp plate overlying the blade and cutter and at its end remote from the cutter secured to the outer clamp plate, and clamping screws interposed between each clamp plate and the plane bit, said outer and inner clamp plates respectively bearing on said cutter beyond and within the end of said cutter blade.

In testimony whereof, I have hereunto set my hand.

PIERRE BASMAISON.
